UNITED STATES PATENT OFFICE.

AUSTIN V. DONOR, OF NEW YORK, N. Y., ASSIGNOR OF ONE-THIRD TO JACOB KLEEBLATT
AND ONE-THIRD TO LOUIS KLEEBLATT, BOTH OF NEW YORK, N. Y.

SCISSORS.

1,123,115.

Specification of Letters Patent. Patented Dec. 29, 1914.

Application filed May 14, 1914. Serial No. 836,499.

To all whom it may concern:

Be it known that I, AUSTIN V. DONOR, a citizen of the United States, and a resident of the city of New York, borough of Manhattan, county and State of New York, have invented a new and Improved Scissors, of which the following is a full, clear, and exact description.

This invention relates to improvements in 10 scissors, and has for an object to provide an improved structure which requires a minimum effort to operate, and which is adapted to open only to a sufficient extent to allow the cutting of threads and other similar work.

A further object of the invention is to provide an improved structure which is limited in its opening movement, and which may be locked in a closed position.

20 A still further object of the invention is to provide a scissors formed so as to open to a small extent, and to readily accommodate the fingers and thumb near the point, whereby a quick easy closing may be had in cutting small articles, as for instance the ends of thread on finished garments.

In carrying out the objects of the invention the body of the scissors is formed with cutting blades comparatively short, and 30 with rounded points so as to prevent the scissors accidentally cutting fabric when only the threads are being trimmed therefrom. One of the blades of the scissors is provided with a finger stop so that the scissors may be properly grasped and held so that the thumb may act in connection with the fingers for quickly and easily closing the blades. A suitable spring is provided at the rear for tending to continually hold the 40 scissors in an open condition. It is to be noted that the scissors formed according to the present invention has substantially the usual stop for limiting the closing action and also a combined stop and lock for limiting the opening movement.

In the accompanying drawings Figure 1 is a front view of the scissors embodying the invention, the same being shown associated with a hand, and with a garment; Fig. 2 is a side view of the device in an open position; Fig. 3 is a side view of the structure shown in Fig. 2, the same being shown closed and locked in a closed position; Fig. 4 is a bottom plan view of the structure shown in Fig. 3; Fig. 5 is a section through

Fig. 2 on line 5—5; Fig. 6 is a section through Fig. 3 on line 6—6; Fig. 7 is a detailed fragmentary top plan view of the points of the scissors disclosing a slightly modified form of the invention.

Referring to the accompanying drawings by numeral, 1 indicates an article and 2 a worked buttonhole from which extends a thread 3. The scissors 4 is intended to be used especially in cutting threads from 65 garments after they are manufactured, and is grasped by the hand as shown in Fig. 1, whereby the scissors may be quickly closed and may also be quickly moved from place to place and operated, a suitable spring 5 70 being used for opening the scissors when released by the hand.

In the manufacture of garments of various kinds after the same have been completed persons known as "examiners" go 75 over the garments and cut off all of the loose threads and ravelings. Persons performing this work find it difficult to perform any considerable amount of work with the ordinary scissors having eyelets at the 80 rear and require scissors that may be grasped near the front so that the same may be easily opened and closed. The present invention is designed to present a structure which will answer the purpose of these 85 workers and accomplishes the object by presenting a structure which normally remains open for a short distance, and which may be readily closed by the hand which grasps the scissors near the front.

The scissors 4 are provided with members 6 and 7 of the usual structure of scissors, and with the rear part shortened so as to provide extensions 8 and 9. Extension 8 has rigidly connected therewith spring 5 which bears against extension 9 and thereby normally holds the scissors open as shown in Fig. 2. The scissors are prevented from opening farther by a stop 10 which is rigidly secured to member 6, and 100 extends through a slot 11 in member 7. Member 7 is provided with notches 12 and 13, notch 13 being provided with a shoulder against which the pivotally mounted member or pawl 14 rests when it is desired to lock the members 6 and 7 in a closed position as shown in Fig. 3. When the scissors are in use or are opened as shown in Fig. 2, pawl 14 is turned over to the position shown in Fig. 5 and may slide back 110

and forth in the notch or slot 12. The front part of the scissors is provided with cutting edges 15 and 16, which edges preferably extend back only a short distance, as shown in Fig. 2. The points 17 and 18 are rounded to an appreciable extent so that there will be no danger of the ends of the scissors accidentally cutting the cloth during the use of the scissors. In fact, these ends are rounded so that looking at the same from the front they appear to be hemispherical in shape. It will also be observed that one of the cutting members of the scissors, namely, member 6, is provided with a finger stop 19, whereby the hand may be properly positioned in respect to the scissors, and any slipping thereof prevented. This also allows the scissors to be held as shown in Fig. 1 which prevents any back and forth movement of the scissors through the hand or any accidental shifting of the scissors while in use. During the shifting of the pawl 14 from the position shown in Fig. 6 to the position shown in Fig. 5 or vice versa, the roughened portion 20 is engaged by the thumb or finger and the pawl readily turned from one position to the other.

In Fig. 7 will be seen a slightly modified form of the invention in which the cutting edges 15' or 16' are curved so that the point 21 will extend at an appreciable angle from the main body of the scissors. This curved structure is intended to allow a free action of the scissors when cutting threads from embroidery, lace and similar articles.

What I claim is—

1. A pair of scissors comprising cutting members pivotally connected together, a spring for normally holding said cutting

members open, a stop rigidly secured to one of said cutting members, the other of said cutting members being formed with a slot through which said stop projects, whereby the movement of the cutting members is limited by the length of said slot. 45

2. A pair of scissors comprising a pair of cutting members, each of the cutting members being formed with a rounded back and rounded points, one of said cutting members being formed with a finger guard or stop near the front end, a spring for normally holding open said cutting members, and means for limiting the opening movement of the cutting members. 50

3. A pair of scissors comprising a pair of cutting members, means for pivotally connecting said cutting members together, a spring for normally holding said cutting members open, a stop rigidly secured to one of said cutting members, the other of said cutting members being formed with a slot through which said stop projects, the cutting member having said slot arranged therein being formed with notches at each 60 end of the slot, a pivotally mounted pawl arranged on said stop and arranged to project into either of said notches for locking either of said notches, whereby the same locks said scissors in a closed position 65 when in one position and allows a free pivotal movement thereof when in another position. 70

In testimony whereof I have signed my name to this specification in the presence of 75 two subscribing witnesses.

AUSTIN V. DONOR.
